ELECTRICAL CONNECTOR

Frederick W. Mebold, St. Louis, Mo., assignor to
 James R. Kearney Corporation, St. Louis, Mo.,
 a corporation of Missouri

Application May 3, 1946, Serial No. 666,856

1 Claim. (Cl. 24—124)

1

This invention relates generally to connectors adapted for use in mechanically and electrically connecting electrical conductors and other elements, and more specifically to the type of connector which is employed extensively in the construction, extension, and repair of electrical systems of various kinds, such as telephone, telegraph, light, and power systems, and which includes a longitudinally slotted, bolt-like member with which is cooperatively associated a nut and washer assembly movable screwthreadedly on said bolt so that wires, or other elements, may be mechanically and electrically clamped between the washer and a portion of the bolt, the predominant object of the invention being to provide a wire connector of this type which includes resilient means adapted to insure application of sufficient pressure against the elements clamped by the connector to produce the desired perfect electrical contact at all times between said elements being clamped and parts of the connector.

It has been found in the use of connectors of the general type to which this invention relates, that due to the softness of the material of elements clamped by the connectors, or because of vibration of suspended wires, or expansion of the connectors, said connectors frequently become loosened in use so that good electrical contact between the connected elements and parts of the connectors is not obtained. The prime purpose of this invention is to provide an improved connector which includes as an integral part thereof resilient means that is adapted to exert positive spring pressure against the clamped elements at all times during use of the connector. Because of this arrangement positive electrical contact is provided between elements connected by the connector when the nut of the connector is drawn up tight, and this positive electrical contact between the clamped elements is maintained by the resilient means of the connector if for any reason any looseness of the connector develops.

Fig. 1 is a side elevational view of the improved connector of the present invention, with parts thereof shown in section.

Fig. 2 is a vertical section taken on line 2—2 of Fig. 1.

Fig. 3 is a horizontal section taken on line 3—3 of Fig. 2.

Fig. 4 is a plan view of a modified form of the washer of the connector illustrated in Figs. 1, 2, and 3.

Fig. 5 is a section taken on line 5—5 of Fig. 4.

Fig. 6 is a section taken on line 6—6 of Fig. 4.

2

Fig. 7 is a plan view of another modified form of the washer of the connector illustrated in Figs. 1, 2, and 3.

Fig. 8 is a section taken on line 8—8 of Fig. 7.

5 In the drawings, wherein are shown for purposes of illustration, merely, several embodiments of the invention, A designates in Figs. 1, 2, and 3 the improved connector generally. The connector A of the views mentioned includes a 10 bolt 1 which is provided with a slot 2 that extends longitudinally of the bolt, said slot being open at one end of the shank portion of the bolt and at its opposite end terminating in a wire seat 3 which is located at the inner portion of the head 15 of the bolt. The spaced apart legs 1' of the bolt 1 are screwthreaded on their outer curved faces, and mounted on said spaced legs is an assembly 4 that includes a nut 5 and a washer 6.

The nut 5 and the washer 6 are permanently 20 associated with each other in such manner that the nut may rotate relative to the washer. The washer comprises an annular portion 6a which surrounds the spaced legs of the bolt 1, the outer marginal portion of said annular portion providing an annular skirt portion which bears edge-wise upon the upper face of the nut 5 (see portions of Fig. 1 which are in section). The washer includes also a relatively narrow bridge portion 6b which extends transversely of the washer and 25 the presence of this bridge portion provides the washer with segmental openings 6c through which the correspondingly shaped legs 1' of the bolt 1 pass. The washer is provided with a pair of fingers 6d which are extended from the skirt portion of the washer at points adjacent to the opposite ends of the bridge portion, these fingers being extended initially inwardly and then downwardly through the bore of the nut. The free ends of the fingers 6d are bent outwardly so that they underlie the lower face of the nut 5 and maintain the nut and washer in such assembled 30 relation as to permit the nut to rotate about the screwthreaded bolt shank while the washer moves in a non-rotatable manner longitudinally of the bolt shank, the bridge portion 6b of the washer 6 moving longitudinally of and within the slot 2 of said bolt 1.

The features of construction of the connector of the present invention which differentiate the 35 connector of the present invention from connectors of the same general type heretofore known has to do with construction and arrangement of the bridge portion 6b of the washer 6 of the connector A, and the material of which said 40 washer is made. In other words, the washer 6 of

the connector of the present invention is made of material which is possessed of considerable inherent resiliency, and the bridge portion $6b$ of said washer is bowed upwardly, as is shown to good advantage in Fig. 2. Also, an important difference between the washer of the connector of the present invention and washers of connectors of the same general type heretofore known, are the substantial free spaces 7 between the opposite end portions of the bridge portion $6b$ of the washer 6 and the inwardly extended, upper portions $6e$ of the fingers $6d$ of said washer, said spaces 7 , and the other features of construction referred to above, serving functions to be hereinafter set forth.

In the use of the connector illustrated in Figs. 1, 2, and 3, the connector A is arranged so that the wires W, or other elements to be connected, pass through the upper portion of the slot 2 of the bolt 1 of the connector. The nut and washer assembly 6 is then screwed upwardly on the shank portion of the bolt 1 to clamp the wires W between the wire seat 3 of the bolt and the resilient and bowed bridge portion $6b$ of the washer 6. The nut and washer assembly 6 is screwed upwardly relative to the bolt shank a sufficient distance to place the resilient bridge portion of the washer under considerable spring tension and this will cause the wires W to be forced together with such pressure that positive electrical contact is obtained between the wires themselves and between the upper wire and the wire seat 3.

It is obvious, that in the use of the connector illustrated in Figs. 1, 2, and 3, the tendency of the connector to become loose due to vibration of the wires, or for any other reason, is eliminated, as the resilient bridge portion $6b$ of the washer 6 takes up any looseness that may develop by continuing to force the wires W into close contact with each other and with the wire seat 3. As to the spaces 7 between the opposite end portions of the bridge portion $6b$ and the inwardly extended, upper portions $6e$ of the fingers $6d$ of the washer 6, it is pointed out that these spaces provide for free resilient movement of the bridge portion of the washer throughout its entire length.

In Figs. 4, 5, and 6 a form of washer 8 is illustrated which is constructed in accordance with the washer shown in Figs. 1, 2, and 3, except that the transverse bridge portion $8a$ of Figs. 4, 5, and 6 is shaped at its center with a V-shaped wire seat 9. The bridge portion $8a$ of the washer 8 shown in Figs. 4, 5, and 6 is bowed upwardly as is shown in Fig. 6, so that it will function in use as does the bridge portion $6b$ of the washer of the

connector shown in Figs. 1, 2, and 3, as previously explained herein.

In Figs. 7 and 8 a washer 10 is illustrated which is provided with a transverse bridge portion that is made up of a pair of bowed, inwardly extended bridge portion extensions $10a$ and $10b$. The sections $10a$ and $10b$ of the bridge portion of the washer shown in Figs. 7 and 8 are so related to each other that they combine to provide the washer 10 with an upwardly bowed bridge portion that functions in the same manner as the bridge portion of the washer 6 of the connector A illustrated in Figs. 1, 2, and 3.

I claim:

15 A connector comprising a bolt having spaced apart shank portions screwthreaded at their outer portions, a nut and washer assembly mounted on said spaced apart shank portions of said bolt, said nut being arranged to move said washer longitudinally of said bolt in a straight-line non-rotatable manner as the nut is screwed longitudinally of the bolt so as to clamp one or more elements between said washer and a part of said bolt, said washer being inherently resilient and said washer being provided with an integral bridge portion that extends through the space between said spaced shank portions of said bolt and is bowed upwardly and is adapted to contact with an element clamped by the connector so as to exert spring pressure thereagainst, said bowed bridge portion being comprised of a pair of arcuate elements having adjacently located free end portions, and means for retaining said washer in such assembled relation with respect to its associated nut that said nut may rotate relative to said washer.
